UNITED STATES PATENT OFFICE.

ROBERT DICKSON, OF HAMILTON, ONTARIO, CANADA.

MATCH-BOX.

1,137,743.

Specification of Letters Patent.

Patented May 4, 1915.

Application filed May 23, 1914. Serial No. 840,490.

To all whom it may concern:

Be it known that I, ROBERT DICKSON, a subject of the King of England, and a resident of Hamilton, in the Province of Ontario and Dominion of Canada, have invented a new and Improved Match Box, of which the following is a full, clear, and exact description.

This invention relates to improvements 10 in match boxes, and has for an object to provide an improved structure which will vend matches one at a time, and will also automatically strike or ignite the same.

Another object of the invention is to provide a vending match box which will 15 close to view the matches to be vended, and which is provided with a magazine for re-loading the vending part of the box.

A still further object of the invention is 20 to provide a reciprocating member in a vending match box and associated devices for feeding one match at a time to the reciprocating member, whereby a single match may be dispensed upon each reciprocation.

In carrying out the objects of the invention 25 a suitable base is provided on which a housing is mounted, the base and housing being constructed and secured together in any desired manner. The top of the housing may be secured in position by screws or 30 other suitable means so that whenever desired the interior of the housing may be examined, and the magazine arranged thereon may be refilled. The housing contains 35 not only a magazine but also is provided with a chute or guideway on one side, whereby the matches may be guided to a proper point, and may be viewed by the operator so that it may be easily seen at all 40 times whether or not the box contains matches. The reciprocating members are arranged so that one acts as a lock for allowing only one match to be dispensed at a time, and the other acts as a dispensing 45 device, whereby the match dispensed is also lighted ready for use.

In the accompanying drawings—Figure 1 is a longitudinal vertical section through a match box embodying the invention; Fig. 2 is a sectional view on line 2—2 of Fig. 1, certain parts being broken away; Fig. 3 is 50 a section through Fig. 2 approximately on line 3—3; Fig. 4 is a detailed fragmentary view approximately on line 4—4 of Fig. 2; Fig. 5 is a fragmentary side elevation of 55 the structure shown in Fig. 1, certain parts

being broken away and the slides being shown in a retracted position; Fig. 6 is a detailed fragmentary sectional view through the upper part of the housing, the 60 same showing the magazine in an elevated position; Fig. 7 is a detailed perspective view of a stopping device for the matches during their discharge.

Referring to the accompanying drawings 65 by numeral, 1 indicates a base of any suitable construction provided with ways 2 and 3 in which a sliding member 4 is mounted. A pair of springs 5 are provided which are secured at one end to the slide 4, as shown 70 in Fig. 1, and at the opposite end to base 1. These springs are intended to normally maintain the slide 4 in the position shown in Fig. 1. The slide 4 is provided with a match receiving groove 6 which merges into 75 finger openings 7, whereby the match may be readily grasped and moved out of the slide. One end of the match receiving groove 6 merges into groove 8 (Figs. 3 and 4) which extends longitudinally of the 80 slide, and is designed to accommodate the head of a match after the match has left the guide 9. A spring 10 (Fig. 4) is secured to the base 1 and extends into the slot or groove 8. This spring may be roughened 85 on the outer surface or left smooth, as desired, and is intended to provide sufficient friction to cause the ignition of the match as the same passes the spring on its way to the outer position or to the position shown in 90 Fig. 1. Associated with slide 4 is a stationary guide 11 provided with a guiding slot 12, as shown in Figs. 1 and 5. Guiding slot 12 is maintained continually opposite the guide 9, and at different times is in registry 95 with the slot 6, and with the loading chamber or loading slot 13 in the auxiliary slide 14. The auxiliary slide 14 is provided with a slot 15 through which extends a post 16 held in place by a screw 17. The screw 17 is provided with an enlarged or elongated 100 head 18 designed to act against the cam surface 19. As shown in Fig. 1 when the slide 4 is moved in the direction of the arrow the same has a considerable movement 105 independent of the auxiliary slide 14, and in fact continuously moves until the post 16 strikes the cam 19, whereupon slide 14 will begin to move and will continue to move until slide 4 has reached its extreme movement, as shown in Fig. 5, whereupon the slot 12 in member 11 will be opposite the 110

slot 6 in Fig. 1. It will be observed that the slot 12 is normally supplied with a match, and when slot 6 is brought into registry therewith the match will automatically drop into slot 6. A yielding member, as for instance, a stop 25 is provided which acts as a buffer when slide 4 together with slide 14 returns from the position shown in Fig. 5 to the position shown in Fig. 1 under the action of springs 5.

The housing 26 is connected to base 1 in any suitable manner, and is provided with a top 27 which is held in place by screws or other suitable means so that when desired the same may be removed for replenishing the magazine 28. The magazine 28 is provided with a back 29 fitting into groove 30, and with a bottom 31 loosely fitting against a solid front 32 arranged in grooves 33. Front 32 is permanently held in the position shown in Fig. 1, while the magazine 28 may be raised and lowered. In front of the front plate 32 is a display plate 34 provided with an opening 35 through which the matches in the guideway 9 may be observed. It will be noted that the front plate 32 falls short of the top of the housing 26. This construction is provided so that the magazine 28 may be raised as shown in Fig. 6 until some of the matches move out into the guideway 9 and fill the guideway, whereupon the magazine may be again loaded with the remaining matches. As the device is used the matches in guideway 9 are dispensed, and when empty or almost empty the magazine can be again raised, as shown in Fig. 6 for replenishing the guideway 9. By this means only a single match is vended or dispensed at a time, and yet means are provided for readily filling the guideway 9.

In order to prevent more than one match being vended at one time a pivotally mounted stop 36 is provided, which stop is formed with bifurcated extensions 37 and 38 (Fig. 7). These bifurcated extensions normally straddle a match as shown in Figs. 1 and 2, and hold said match and the matches above the same from falling into the loading chamber or slot 13 or slide 12 while there is a match already in slot 12. The proportions of the various parts are such that when the slides 4 and 14 are moved rearwardly the slot 13 will be moved out of registry with guideway 9 and slot 12 before slot 6 is brought into registry with the slot 12. This structure is clearly illustrated in Fig. 5 wherein it will be seen that the member 18 engages cam 19 and raises the pivotally mounted stop 36 so that the lowermost match in the guideway 9 is released. Upon the return of the slides 4 and 14 the lowermost match will drop into the loading chamber or slot 13 and from thence into slot 12, and the bifurcated members 37 and 38 will catch the next match and hold the

same from movement as member 18 moves from beneath cam 19 when slide 14 is moved so that the loading chamber or slot 13 will be in registry with guideway 9.

In operation when it is desired to secure a lighted match the thumb is pressed against the end of slide 4 carrying the extension 39, and a finger is placed in the socket 40 in the stationary plate 41. The thumb is then brought up to a position adjacent the finger, whereby the slide 4 will be moved to the rear, as shown in Fig. 5, and the other parts associated therewith will be properly actuated as heretofore described. This will allow the lowermost match to drop into the slot 6, as shown in Fig. 5. Upon releasing the slide 4 the same will automatically move under the action of springs 5 to the position shown in Fig. 1. Upon slide 4 moving in this manner the end of a match arranged in slot 6 will contact with the friction member or spring 10 and ignition thereof will result. As the end or head of the match is in slot or notch 8 the same will burn until it reaches the atmosphere, whereupon the match may be removed by placing the fingers in the finger notches 7. It will of course be understood that the movement of the slide 4 from the position shown in Fig. 5 back to the position shown in Fig. 1 is a quick one, and therefore the match will have no time to go out.

What I claim is—

1. In a match box of the character described, a base, a housing arranged on said base, means associated with said housing defining a magazine and a match guiding channel leading therefrom, a principal slide arranged on said base, an auxiliary slide arranged in said base, means for connecting the principal slide with the auxiliary slide, means actuated by a projection from the main slide for regulating the flow of matches from said guiding channel, said primary sliding member being formed with a groove for receiving a match, and means for resiliently holding said primary sliding member in a predetermined position.

2. In a match box of the character described, a reciprocating dispensing member provided with a match receiving groove, a guiding slot co-acting with said groove, a housing adapted to contain matches, means for directing a stream of matches from said housing to said guiding slot, means for allowing one match to enter said guiding slot at one time, and means covering said guiding slot while the same is in registry with the groove in said reciprocating member.

3. In a match box of the character described, a housing provided with a guiding channel for matches, a pivotally mounted stop arranged to hold said matches against movement when in one position, and to allow the lowermost of said matches to move

- downwardly when in another position, means formed with a guiding slot for receiving said lowermost match, a reciprocating sliding member provided with a match receiving groove, a projection extending from said reciprocating member adapted to engage and move pivotally mounted match stop, and means actuated by said reciprocating member for covering said guiding slot when the match receiving groove in said reciprocating member is in registry with the guiding slot.
4. In a match vending box of the character described, a housing provided with a match guiding channel, said channel being open on one side at the top, a magazine arranged in back of said channel formed with an open side facing said channel, said magazine being adapted to be reciprocated, whereby matches therein may be raised so as to pass through said opening into said channel, means for feeding one match at a time from said channel, and means for abrading each of said matches as the same is fed from said channel to a point of utilization, whereby the match is delivered in a burning condition.
5. In a match box of the character described, a receiver, means for guiding matches from said receiver, a pivotally mounted stop co-acting with said guiding means, said pivotally mounted stop being provided with bifurcated extensions adapted to straddle the lowermost match when the stop is in one position, and to release said lowermost match when in another position, one portion of said bifurcated extensions moving beneath the remaining matches so as to allow only the lowermost match to pass from said guiding means, a reciprocating member for receiving and delivering said lowermost match, and means actuated by said reciprocating member for moving said stop.
6. In a match box of the character described, a housing provided with a match guiding member, means defining a guiding slot, a reciprocating delivery member provided with a groove designed to register at times with said guiding slot so as to receive a match therefrom, means for covering said guiding slot when the guiding slot is in registry with said groove, and means engaging the end of said match for abrading the same immediately previous to the delivery of the match by said reciprocating delivery member.
7. In a match box of the character described, a reciprocating member provided with a match receiving groove, a stationary member arranged above said reciprocating member, said stationary member being formed with a guiding slot, a reciprocating member above said stationary member, said last mentioned reciprocating member being provided with a loading chamber normally in line with said guiding slot, means connected with said first mentioned reciprocating member after the first mentioned reciprocating member has moved a predetermined distance, whereby the loading chamber in the second mentioned reciprocating member is moved from registry with said guiding slot before the groove in the first mentioned reciprocating member has been brought into registry with said guiding slot, means for feeding matches into said guiding slot through the loading chamber in the second mentioned reciprocating member, and means for returning said reciprocating members to their former position.
- In testimony whereof I have signed my name to this specification in the presence of two subscribing witnesses.
- ROBERT DICKSON.
